A technical drawing showing a cross-section of a cylindrical part. The part has a central vertical slot. Various dimensions are labeled around the perimeter and through the slot: 86 at the top, 80 and 114 on the left, 106 and 110 on the right, 108 at the bottom, and 84 at the very bottom. The drawing is labeled 'Fig. 1' in the top right corner.

OIL WELL BAILER

James D. Johnston, Smackover, Ark.

Application September 20, 1941, Serial No. 411,742

3 Claims. (Cl. 166—19)

My invention relates to sand pumps or bailers of the type employed in oil wells, and has among its objects and advantages the provision of an improved suction pump of novel telescopic construction.

In the accompanying drawings:

Figure 1 is a sectional view of a pump in accordance with my invention;

Figure 2 is an enlarged sectional view of the upper end portion of the structure of Figure 1;

Figure 3 is a sectional view along the line 3—3 of Figure 2;

Figure 4 is a sectional view along the line 4—4 of Figure 2;

Figure 5 is an enlarged sectional view of the lower end of the pump structure of Figure 1;

Figure 6 is a sectional view along the line 6—6 of Figure 5;

Figure 7 is a sectional and elevational view of connector parts for detachably connecting the inlet valve structure with the lower end of the pump;

Figure 8 is a view illustrating a latch for the parts of Figure 7;

Figure 9 is a sectional view illustrating the latch in its open position;

Figure 10 is a sectional view of the latch in a released position;

Figure 11 is a top plan view of the inlet valve;

Figure 12 is an enlarged longitudinal sectional view of a portion of the pump structure;

Figure 13 is a sectional view along the line 13—13 of Figure 12;

Figure 14 is a longitudinal sectional view of the telescopic parts of the modified pump structure;

Figure 15 is a partial sectional view of a connector for the pump cable;

Figure 16 is a sectional view of a different form of connector; and

Figure 17 is an elevational view of the connector of Figure 16.

In the embodiment selected for illustration, I make use of a cage 20 having a threaded shank 22 to which is threadedly connected an eye 24 for connection with the rope or cable employed in manipulating the pump in the well casing. Inside the cage 20 is mounted a ball valve 26 normally lying on a seat 28 formed on one end of a sleeve 30. This sleeve is provided with a flange 32 secured between an internal flange 34 of the cage 20 and the end of a threaded tubular neck 36 formed on a cap or connector member 38 having a longitudinal bore 40 communicating with the cage through the medium of the sleeve 30.

An outside tube 42 is welded at 44 to a bushing nut 46 threadedly connected at 48 with the cap 38. At the lower end of the cap 38 is formed a shank 50 of smaller diameter than the inside diameter of the bushing nut 46 to provide an annular space 52 having communication with the bore 40 through the medium of ports 54.

A threaded bore 56 is provided in the lower end of the shank 50 for connection with a threaded stem 58 formed on the upper end of a rod 60. The rod 60 extends through a ring 62 secured to the upper end of an inside tube 64 having telescopic relationship with the tube 42. The ring may be secured to the tube 64 by pins 66, and the inside diameter of the ring is such as to provide an annular space 68 about the rod 60. To the lower end of the rod 60 is secured a head 10 freely slidable in the tube 64 and arranged to engage the ring 62 upon predetermined elevation of the tube 42 with respect to the tube 64.

The lower end of the tube 64 is welded at 72 to a sleeve 74. Pins 76 may also be used for connecting the tube and the sleeve. A valve unit 78 is carried by the lower end of the sleeve 74. This unit comprises a sleeve 80, see Figure 5, welded at 82 to the tube 74. A tubular bottom member 84 is threadedly connected at 86 with the sleeve 80 and is provided with inlet ports 88 near its bottom end as well as a large bottom opening 90.

A conically shaped valve 92 is located at the upper end of the member 84 and includes two sections 94, each pivotally connected at 96 with the member 84. Figure 5 illustrates the sections 94 in their closed positions, and the sections may pivot upwardly to permit passage of material being pumped to a position above the valve. Bottom member 84 is detachably connected with the sleeve 80. The sleeve is provided with internal threads 98 and longitudinal slots 100 extending ninety degrees circumferentially of the sleeve. Similarly the member 84 is provided with threaded rib-like formations 102 receivable in the grooves 100 when aligned therewith. Thus the member 84 may be connected with the sleeve 80 by pushing the neck 104 into the sleeve 80 and then imparting a ninety degree rotation to the member 84, which brings the threads 98 and 102 to full engagement.

A latch member 106 normally lies in a groove 108 in the member 84 and is pivotally connected to the latter at 110. The end 112 of the latch member is receivable in a slot 114 in the sleeve 80 when pivoted to the position of Figure 9 so as to

latch the member 84 against accidental rotation relatively to the sleeve member.

In operation, the bailer is lowered into the well casing and as the member 84 engages the bottom of the well, the outer tube 42 descends downwardly on the inner tube 64, air in the two tubes finding its escape through the cage 20. As an upward pull is exerted on the bailer, the outer tube 42 moves upwardly on the inner tube 64, with the result that suction created by reason of the relative movement between the two tubes causes the material to rise in the bailer.

The head 70 engages the ring 62 for lifting the tube 64 from the well. With the head 70 lying in engagement with the ring 62, the lower end of the tube 42 lies above openings 115 in the inner tube 64.

With the loaded bailer elevated to the surface, the bailer is unloaded by detaching the bottom member 84 from the sleeve 80, the uncovered 20 openings 115 placing the tubular structure of the bailer in communication with the atmosphere so that the material in the inner tube 64 may flow freely from the bailer.

The valve 92 closes immediately as the lower 25 end of the bailer structure is lifted off the bottom of the well.

Figure 14 illustrates a bailer in which the outer tube 116 is provided with two diametrically opposed openings 118. The inner tube 120 is provided with slots 122 so arranged that at least one slot will always register with at least one opening 118 when the head 124 is brought into engagement with a bushing 126 welded at 128 to the outer tube 116 and additionally secured thereto by pins 130. Head 124 includes a shank 136 provided with a longitudinal bore 138 normally closed by the ball valve 140 in the cage 142. The head also includes a shank 144 threadedly connected with the inner tube 120, and the shank 136 slides freely in the bushing 126 so that the shank and the cage 142 may pass therethrough as the inner tube 120 descends in the outer tube 116 when the latter strikes bottom.

The bailer of Figure 14 includes a lower end structure corresponding to that illustrated in Figures 5 through 11. Figure 15 illustrates the cage 142 as being threadedly connected at 145 with an eye 146 to which the manipulating rope is attached. In Figures 16 and 17, a cable 148 is illustrated as being inserted in a socket 150 in a connector 152, the connector being provided with an opening 154 to facilitate application of a sol-

dered connection between the cable and the connector. Connector 152 may also be threadedly connected at 156 with a cage 158.

Without further elaboration, the foregoing will so fully illustrate my invention, that others may, by applying current knowledge, readily adapt the same for use under various conditions of service.

I claim:

1. A bailer of the type described comprising telescopically related upper and lower tubes, each tube being of uniform diameter from end to end with one tube fitted closely inside the other, an inlet valve at the lower end of the lower tube, an air exhausting valve at the upper end of the upper tube, said upper and lower tubes being of such length and so fitted as to create suction therein when the tubes are extended, the lower tube being provided with openings near its upper end above which the lower end of the upper tube moves when the tubes are fully extended, and a lost motion connection between the upper and lower tubes to lift the lower tube with the upper tube when the tubes are fully extended.

2. A bailer of the type described comprising telescopically related upper and lower tubes, each tube being of uniform diameter from end to end with one tube fitted closely inside the other, an inlet valve at the lower end of the lower tube, an air exhausting valve at the upper end of the upper tube, said upper and lower tubes being of such length and so fitted as to create suction therein when the tubes are extended, a ring fixed within the lower tube, and a rod fixed to the upper tube and provided with a head engageable with the ring for lifting the lower tube with the upper tube when the tubes are fully extended.

3. A bailer of the type described comprising telescopically related upper and lower tubes, each tube being of uniform diameter from end to end with one tube fitted closely inside the other, an inlet valve at the lower end of the lower tube, an air exhausting valve at the upper end of the upper tube, said upper and lower tubes being of such length and so fitted as to create suction therein when the tubes are extended, a cap on the upper end of the upper tube constituting a mount for the air exhausting valve, said cap being tubular and provided with air openings, a ring fixed within the lower tube, and a rod fixed to the cap provided with a head engageable with the ring for lifting the lower tube with the upper tube when the tubes are fully extended.

JAMES D. JOHNSTON.
